UNITED STATES PATENT OFFICE.

WILLIAM ERASTUS WILLIAMS, OF CHICAGO, ILLINOIS.

HUB DEMOUNTABLE DOUBLE DISK WHEEL.

1,425,926.

Specification of Letters Patent. Patented Aug. 15, 1922.

Application filed September 23, 1920. Serial No. 412,158.

To all whom it may concern:

Be it known that I, WILLIAM ERASTUS WILLIAMS, a citizen of the United States, a resident of Chicago, in the county of Cook and State of Illinois, have invented a new and useful Improvement in Hub Demountable Double Disk Wheels, of which the following is a specification.

The object of the invention is to produce very strong, light, inexpensive disk wheels for automobiles so constructed as to be readily demounted at the hub.

Reference will be had to the accompanying drawing in which Figure 1 is a front elevation of the wheel.

Figure 2 is a transverse sectional elevation on a larger scale than that of Figure 1.

Figure 3 is an enlarged detail of the rim fastening shown in cross section on line 3—3 of Figure 1.

Figure 4 is an enlarged detailed sectional view at the connection of the hub, showing the demountable disk parts only.

Figure 5 is a sectional detail of a piece of the hub.

In the drawing 1 indicates the ordinary hub, here shown as the rear hub in an ordinary automobile wheel and 2 indicates the brake drum. This brake drum 2 is secured by a series of bolts 3 to a flange 4 on the hub.

The hub has peripheral, outwardly inclined, machined surfaces 5 and 6. The web of the wheel is here shown as being made of two disks of metal, the rear disk being indicated by 7 and the front disk by 8. The front disk is shown having concentric corrugations 9 which add to the appearance and to the local stiffness against indentation from accidental causes and further give a slight degree of elasticity in the rotative action of the wheel itself. The two disks 7 and 8 are secured in the hub zone to an angular ring having a horizontal flange 10 and vertical flange 11.

The rear disk 7 is provided with an inwardly turned flange 12 which extends under the flange 10 of the hub ring and is secured thereto by a series of rivets 13. The edge 10 of the disk 7 where it turns under the edge of the flange 10 of the angular ring bears directly on the inclined surface 6 of the flange 4 of the hub.

The front disk 8 extends down the front

face of the flange 11 of the angular ring and is turned over on the inside of the said flange 11 as is indicated by 14, thus locking the inner edge of the disk 8 to the angular ring. In addition to this locking feature of the turned over edge of the aperture of the disk 8, I secure the disk 8 to this flange 11 by a series of rivets 15. To better grip the metal of the disk 8 to the flange 11 through the medium of the rivets 15 I provide a clamping plate 16 through which the rivets 15 pass, thus clamping the angular ring, the body of the disk and the plate 16 into a unitary structure.

The inner edge of the disk around the inner aperture, where the disk is turned over into the flange 14, furnishes the bearing surface 17, (see Figure 4), which rests directly upon the inclined bearing surface 5, (see Figure 5) of the hub. The inner edge of the ring 16 is also beveled to fit the bearing surface 5 as is indicated by 18.

The outer margin of the ring 16 is made to fit a gentle swell or outwardly extending bulge 19 of the disk 8, thus shouldering the disk, as it were, on the edge 20 of this ring 16, the purpose being to furnish as large a cross section of the disks 7 and 8 as possible within reasonable limits of diameter around the hub whereat the load strains are carried, as this region occasions the greatest fibre stresses on the metal of the disks.

A series of studs 21 are threaded into the hub at 22 and are provided with a series of round headed nuts 23 which furnish the means for bolting the disks 7 and 8 in a detachable form on to the hub.

The disks 7 and 8 join each other at the rim and are provided with registering flanges 24 and 25 on the margins of the disks and are clamped to each other and to the flange 26 of the main portion 28 of the rim through a series of rivets 27. Thus the main rim portion, the disks and annular ring having flanges 10, 11, form a unitary structure which may be mounted upon the hub and demounted by means of the studs 21.

The inclined surfaces 5 and 6 on the hub are such as to furnish a tight registering fit for the demounting fastening and yet come off easily when the nuts 23 are removed. The nuts, 23, being provided with the internally threaded sleeve portions 29, permit when removed, lateral movement of the demount-

able structure with reference to the studs, whereby mounting and demounting are facilitated.

The arrangement of the two disks connected together in the hub region and at their margins may be used with a variety of rims but I prefer to use it with the type of rim here shown in which the arrangement of the parts makes a very desirable wheel construction, in that the skid shocks on the disks are taken up by the two disks being well braced against each other at the hub juncture and well connected together at the rim making the well known triangular strain lines so essential in an economical design of braced structures.

The type of rim here shown is one wherein the side ring is a removable ring or flange indicated by 30 having the tread seat 31, 20 which rests under the bead of the tire, the latter being shown in dotted lines in Figure 2.

A series of studs 32 having elongated heads 33, which approximate the old door button in appearance, are screwed into special nuts 34 on the inside of the flange 26 of the main rim. These studs 32 are screwed home with the heads 33 against the flange 26 before the tire is inflated and are 30 arranged to fit tightly against this flange when the heads are approximately radial with respect to the wheel.

The detachable ring 30 is divided at Fig. 1, and provided, on opposite sides of 35 the cut, with blocks 36 having projections 37 which engage undercut portions of the flange 26 and rim 28 and, hold the ring 30 against radial displacement. However, the flange 31 of the side ring, resting under the 40 bead of the tire is held in place by the tire pressure so that the chief function of the blocks 36 is to register the ends of the ring 30 centrally on to the head of the special stud 38, so that at all times the ring 30 may 45 be made to have its ends held by the same head 33 and prevent the careless operator from placing the ring 30 on to the rim with the open ends between the studs instead of directly underneath the head of the stud.

50 In the side of the ring 30 I emboss projections 39 which project outward on each side of the inner end of the elongated heads 33 of the studs 32 to act as detents or registering points to prevent the revolution of the studs when the tire is inflated. The 55 smallest amount of inflation will make a side pressure on the ring 30 that will hold these projections 39 so tightly in contact on each side of the heads 33 of the studs that 60 it will be practically impossible to turn the studs. But when the tire is deflated the ring 30 may be pressed inward slightly so as to permit the turning of these heads 33, 90 degrees as is shown by a position 65 in Figure 1.

Thus by turning the heads 33 of the studs 32, 90 degrees with the tire deflated, the ring 30 is easily removed and the tire changed with a minimum amount of trouble.

Claims:

1. The combination with a hub having 70 annular correspondingly inclined bearing surfaces unequally distant from its axis, of two inwardly divergent wheel disks having unequal central openings to fit over said 75 surfaces, respectively, and clamping means for forcing the disks laterally against the inclined bearing surfaces.

2. In a wheel of the class described, a unitary wheel body having a rim and front 80 and rear circumferentially united wheel disks spaced apart centrally, by a ring having a flange parallel to the plane of the wheel and an axially extending flange, said disks being bent over the margins of the 85 flanges, respectively and fixed to the flanges.

3. The combination with front and rear disks of a wheel meeting circumferentially and diverging inwardly, of a central angular spacing ring having a flange parallel to 90 the plane of the wheel and a flange perpendicular to that plane, the flanges being rigidly fixed to the spaced portions of the disks, respectively, and the marginal portion of each disk being turned over the edge 95 of its flange, and means for detachably securing the disks and ring to a hub.

4. In a wheel of the class described, the combination with a spacing block having a flange parallel to the plane of the wheel 100 and a second flange extending axially with respect to the hub and adapted to fit a suitable hub, of wheel disks engaging the margins of said flanges, respectively, and means for clamping the block and disks 105 laterally against portions of a suitable hub.

5. In a wheel of the class described, disks forming the web of the wheel and connected together and to the rim at the margins of the disks and said disks separated from each other at the hub connection; a separator ring having a flange parallel to the plane of the wheel and an axially extending flange, said disks being secured to said flanges, respectively, and a clamping ring on 115 the outside of the disk outside of the flange first mentioned, and fastening means passing through the said clamping ring, the body of the disk and the said first mentioned flange of the said separator ring. 120

6. In a wheel of the class described, disks forming the web of the wheel and connected together and to the rim at the margins of the disks and said disks separated from each other at the hub connection; a separator ring having a flange parallel to the plane of the wheel and a flange perpendicular to that plane, and a clamping ring on the outside of the disk outside of the first mentioned flange, and fastening means 125 130

passing through this said clamping ring the body of the disk and the said first mentioned flange of the said separator ring, and a series of bolts passing through the said 5 clamping ring the metal of the disk and the radial flange of the separator ring for securing the same to the hub.

7. In a wheel wherein disks form the web of the wheel, a front disk and a rear disk 10 separated from each other at the hub connection by a spacer block and said block provided with an axially extending portion to which one disk is fastened and a portion, parallel to the plane of the wheel to which 15 the other disk is fastened, and said last mentioned portion of said spacer block being of smaller diameter than the axially extending portion; the metal of each disk being turned over in overlapping form on 20 the edges of their respective portions of the spacer block.

8. In a wheel wherein disks form the web of the wheel, a front disk and a rear disk 25 separated from each other at the hub connection by a spacer block and said block provided with an axially extending portion to which one disk is fastened and a portion, parallel to the plane of the wheel to which 30 the other disk is fastened, and said last mentioned portion of said spacer block being of smaller diameter than the first mentioned portion; the metal of each disk being turned over in overlapping form on the edges 35 of their respective portions of the spacer block, and suitably secured thereto, and a

clamping ring outside of the disk and that portion of the separator block which is parallel to the plane of the wheel, in combination with a series of bolts passing through the clamping ring and the portion of the 40 separator block which is parallel to the plane of the wheel for securing the parts to the hub.

9. In a wheel having disks forming the web members and spaced apart from each 45 other at the hub and held apart by a separator block of angular cross section, one flange of the angular cross section lying in a circumferential arrangement approximately parallel with the axis of the wheel 50 and another flange extending approximately radially to the axis of the wheel, in combination with suitable fastening means for securing the disks and separator block laterally against a suitably formed hub. 55

10. In a wheel having disks forming the web thereof and separated from each other at the hub region by an angular spacer block having two flanges to receive the 60 disks, the metal of each disk turned over the edges of the flanges respectively and fastened thereto and the said disks and spacer block suitably secured to a hub.

Signed at Chicago, in the county of Cook and State of Illinois, this 7th day of September, 1920. 65
